(57) **CLAIM**

The ornamental design for a seed propagation frame, as shown and described.

DESCRIPTION

FIG. 1 is a front perspective view of a seed propagation frame showing my new design;

FIG. 2 is a rear perspective view thereof;

FIG. 3 is a smaller scale top plan view thereof;

FIG. 4 is a smaller scale left side elevation view thereof;

FIG. 5 is a smaller scale right side elevation view thereof;

FIG. 6 is a smaller scale bottom plan view thereof;

FIG. 7 is a front perspective view of the design of FIG. 1 in use;

FIG. 8 is a front perspective view of a second embodiment thereof;

FIG. 9 is a rear perspective view of FIG. 8

FIG. 10 is a smaller scale top plan view of FIG. 8

FIG. 11 is a smaller scale right side elevation view of FIG. 8, the left side elevation view being a mirror image thereof; and, FIG. 12 is a smaller scale bottom plan view of FIG. 8.

The broken lines in the drawings are included to show features that form no part of the claimed design.

My seed propagation frame is intended to support an avocado seed partially submerged in water for purposes of propagation.
